(57) **CLAIM**

The ornamental design for a ceiling fan, as shown and described.

DESCRIPTION

FIG. 1 is a front elevational view of the first embodiment of a ceiling fan showing the new design;
FIG. 2 is a rear elevational view thereof;
FIG. 3 is a left-side elevational view thereof;
FIG. 4 is a right-side view thereof;
FIG. 5 is a top plan view thereof;
FIG. 6 is a bottom plan view thereof;
FIG. 7 is a front perspective view thereof;
FIG. 8 is a front elevational view of the second embodiment of a ceiling fan showing the new design;
FIG. 9 is a rear elevational view thereof;
FIG. 10 is a left-side elevational view thereof;
FIG. 11 is a right-side elevational view thereof;
FIG. 12 is a top plan view thereof;
FIG. 13 is a bottom plan view thereof; and,
FIG. 14 is a front perspective view thereof.
The broken lines depict portions of the ceiling fan that form no part of the claimed design.

1 Claim, 10 Drawing Sheets
